UNITED STATES PATENT OFFICE.

GEORGE W. BUFFORD, OF BUFFALO, NEW YORK, ASSIGNOR TO J. H. WILLIAMS & COMPANY, OF BROOKLYN, NEW YORK, A CORPORATION OF NEW YORK.

CHAIN PIPE WRENCH.

1,416,685.

Specification of Letters Patent. Patented May 23, 1922.

Continuation of application Serial No. 64,266, filed November 30, 1915. This application filed June 30, 1921. Serial No. 481,723.

To all whom it may concern:

Be it known that I, GEORGE W. BUFFORD, a citizen of the United States of America, residing in Buffalo, in the county of Erie 5 and State of New York, have invented certain new and useful Improvements in Chain Pipe Wrenches, of which the following is a specification.

The invention relates to chain pipe 10 wrenches and aims to provide improvements therein.

The present invention provides a chain pipe wrench which, without change or adjustment of parts, readily and effectively 15 grips pipe, fittings or flanges. Such a tool is of considerable convenience to pipe fitters, as it enables them to effectively turn pipe, fittings and flanges, all of which work is usually a part of an installation, with a 20 single tool. The invention further provides a tool of the character described, capable of effectively gripping a range of sizes of pipe without change or adjustment. The invention further provides a strong and durable 25 tool.

The invention also provides such a tool in which the jaws are reversible, by which a new working face of the jaw may be brought into action when the teeth of one face 30 becomes worn or broken.

The invention further provides a convenient, strong, and readily formed joint between the reversible jaw and stock or head. The invention also includes other improvements 35 which will be hereinafter more fully described.

Referring to the drawings which illustrate several forms of the invention,—

Figure 1 is a side elevation of one form 40 of the invention showing the wrench in engagement with an elbow;

Fig. 1^a is a side elevation of the wrench shown in Fig. 1, showing the wrench applied to a pipe;

Fig. 1^b is a side elevation of the wrench shown in the foregoing Figures 1 and 1^a, showing the wrench applied to the flange of a flange fitting;

Fig. 2 is a top or plan view with the chain 50 removed;

Fig. 3 is an underside view with the chain broken away;

Fig. 4 is a longitudinal section through the jaw.

Referring to Figures 1 to 4, let A indicate the wrench handle and B the jaw. The jaw B may be formed integrally with the handle and in extent has a length corresponding to the length of the face *a b* of Fig. 1.

The jaw B, however, may be formed separately as a reversible jaw, and when so formed is practically double the length of the usual construction, so that it not only includes the working face *a b*, but also the 65 working face *a c*, which faces closely adjoin. It will be noticed that the teeth of such working faces incline in opposite directions. In the present construction the jaw B is formed as one structure with a 70 width indicated at *d e*, in Fig. 3. However, the working faces do not extend completely from side to side at all portions of the jaw, such working faces being interrupted at *f* and *g* (as shown in this figure) to form recesses into which the handle A and chain C 75 may extend. By forming the working faces with a substantial portion extending over the complete width of the jaw, the latter is enabled to grip fittings and flanges which 80 would not be practicable or possible if two separate jaws were employed. The forward divided part of the jaw is especially useful on straight pipe work, and the undivided part is best for flanges (using a 85 flat chain), and fittings can be gripped to advantage with either part of the jaw.

In Fig. 1 the wrench is shown engaging a fitting, the teeth on the broad part biting the fitting. In Fig. 1^a the wrench is shown 90 engaging a pipe, the teeth on the bifurcated portion engaging the pipe. And in Fig. 1^b the wrench is shown as engaging a flange, the teeth on the broad or undivided part engaging the flange.

The jaw B is formed with a hole *h* by which it is fastened to the handle, the latter having a corresponding hole, and a bolt *i* is provided which passes through the handle and jaw. The handle is bifurcated to form 100 arms *j k*, which receive between them a central web *m* formed on the jaw, and on either side of the web the jaw is recessed (see *n*, Fig. 1) to receive lugs *o* formed on the

handle. When the bolt *i* is tightened the jaw is prevented from moving around its pivot by the portions *p*, *p* of the lugs which form stops engaging the inner faces *q*, *q* of the jaw.

In this type of wrench the chain is not pivoted at the end of the handle, but is usually pivoted to the handle at a point at the rear of the reversible jaw; in the construction shown the handle is provided with lugs *r*, *r* spaced apart to receive the chain. The close joining of the faces *a b* and *a c* of the jaw, and the short radius of curvature, permits making the latter of minimum length which can be easily accommodated in the space forward of the lugs *r r* without making this space too great for efficiency in operation. The chain is passed beneath the work, as indicated in Fig. 1, and is engaged with locks such as *s s*, spaced apart to permit the chain to pass between them, and formed with the usual locking recesses. The relative locations of the lugs *r* and *s* and jaw, and the size and shape of a jaw for a wrench for a medium range of pipe (from $3\frac{3}{8}$ " to $2\frac{1}{2}$ ") shown in the drawings, are such as to give good results. The radius of curvature of the jaw is about two inches for a wrench for pipe of the range indicated; the jaw has about the same width as the radius; the points (*r s*) from which the ends of the loop formed by the chain swing, are spaced apart a distance approximately equal to that of the radius of curvature of the jaw; the pin *w* in the jaw *r* is on a tangent drawn substantially at the lowest point of the jaw; and the lugs *s* are approximately at the center *bx* of curvature of the jaw. The jaw is best provided with a groove *t* which receives one of the links of the chain, such as *u*, when the wrench is used on pipes having small diameters. Moreover, in order that the bifurcated ends of the jaw (at each side of the spaces *f* and *g*) may be of the requisite strength, the corners between the bifurcated and full portions of the jaw are filled in with metal, as indicated at *f'*, *g'*, being preferably rounded, as shown in Figs. 2 and 3. The links *u* which lie horizontal may bear against these rounded portions *f'*, *g'*, and thus lie close to the bottom of the bifurcation.

When the front working face has become dulled or impaired in use, the bolt *i* is removed and the jaw turned end for end, whereupon the bolt is replaced and tightened. The working face which has formerly occupied the rearward position is thereby brought into active position. By this means the jaw has a double length of life before it is necessary to sharpen it or substitute a new jaw therefor. So also, if a jaw becomes too dull or injured to sharpen, the entire wrench is not thereby necessarily

discarded, but may be rendered practically new by the substitution of a new jaw.

The type of wrench illustrated with the chain pivotally connected at a point in the rear of the jaw and with the lock located on the side of the wrench opposite that on which the pipe is gripped, permits the wrench to work only in one direction and to use only the outermost or forward face of the jaw. This is a safety feature when using the wrench in an upright position. Such wrenches have sometimes to be used overhead and the accidental release and fall of the chain would be liable to injure the user. With wrenches of the type here illustrated there is not the same liability to accidental release of the chain as in wrenches working both ways.

The sharp curve of the jaw permits of close work on pipes in corners, and when pipes are spaced close together, as in radiator coil work. The jaw, it will be observed, is embraced between the points (*r s*) at which the ends of the link of the chain are fastened. Also, the pivoting of the chain on the handle back of the jaw allows four distinct holds on each size pipe in most cases, and three in all cases, as against two or one hold in other makes, thereby distributing the wear more evenly over the teeth on the jaw. These grips or holds are all obtainable on the forward half of the jaw, and when the teeth become worn on the forward half the jaw can be turned, as above explained, to use the teeth of the other half. The wide jaw and the length of chain between its point of bearing on the pipe and the fixed point on the handle give the wrench a firm grip with the least marring of the pipe. The design and proportions make a wrench which can be placed on a pipe with comparative ease. It is not easy to place it in any but the correct position, and no thought is required to do this. The jaw on one side of the wrench only, makes it possible to insert the wrench into smaller spaces than are accessible to a wrench with a double jaw.

In my wrench a new jaw can be substituted for the old one in case of breakage, and can be attached with greater ease than in other styles of wrench having a jaw of the same general shape. Any ordinary user of the wrench, without being a skilled workman, can attach a new jaw, using either a bolt, as shown, or any other style of pin for the purpose. Also, the special swinging link attached to the lug *r* may be dispensed with and the first link of the chain attached directly to this lug, and the chain may be a cable chain, as shown, or any other style of chain, depending on the use to which the wrench is to be put, as a flat chain where flanges are to be gripped by the wrench. The lugs *r* are fastened to the swinging

link by a pin which can be easily driven out to permit a reversal of the chain end for end, the link at the free end of the chain being then fastened to the lugs *r* by the 5 same pin. As most of the wear on the chain is near the fastened end, a double life of the chain is made possible in this way. When no special swinging link is used, of course both ends of the chain are alike and consist 10 only of the ordinary links, and the reversal is all the easier. The lugs *s* are beveled toward the outside, as shown in Fig. 2, which facilitates the use of either type of chain. The dotted lines in this figure indicate 15 the contour of the bearing faces of the lugs *s*. The inner curve of these bearing faces conforms to the rounded end of a link of a cable chain, and if the lugs were not thus shaped they would in time cut notches 20 in the links.

The curve *n* (Fig. 1) of the recesses on the outer side faces of the jaw is preferably circular, as shown, to give room for a wrench to engage the head of the bolt *i* and 25 the nut thereon with the least loss of material in the jaw, and, consequently, with the greatest strength of the jaw. This is also the cheapest and best form for manufacturing purposes, as a polygonal shape would 30 be more expensive to mill. The curved shape also gives greater ease in assembling, and a better joint between the jaw and the handle.

The invention may receive other embodiments than that herein specifically illustrated and described.

This application is a continuation of an application filed November 30, 1915, serially numbered 64,266.

40 What is claimed is:

1. In a chain pipe wrench, the combination of a handle, a reversible jaw having working faces at the forward and rear parts of the same side of the jaw, a chain attached to the handle at the rear of both working faces and consequently arranged to grip a pipe and turn it by engagement with a forward working face only of said jaw, said jaw having its forward and rear ends 45 bifurcated to permit the passage of the chain and having a central portion of the full width of the jaw, said jaw being adapted to be turned end for end so as to bring into forward operative position one or another of said working faces.

2. In a chain pipe wrench, the combination of a handle, a reversible jaw having working faces at the forward and rear parts of the same side of the jaw, the respective 50 faces formed of oppositely inclined teeth and being substantially continuous, and a chain attached to the handle at the rear of both working faces and consequently arranged to grip a pipe and turn it by engagement with a forward working face only

of said jaw, said jaw being adapted to be turned end for end so as to bring into forward operative position one or another of said working faces, and said jaw having its forward and rear ends bifurcated to permit the passage of the chain and having a central portion of the full width of the jaw.

3. In a chain pipe wrench, the combination of a handle, a jaw having forward and rearward working faces and adapted to be turned end for end, a pin for attaching said jaw to said handle, said handle having lugs *o* and said jaw having recesses on its outer side faces in which said lugs lie in the fastened position, said jaw having circular faces *n* surrounding an edge of said lug.

4. In a chain pipe wrench, the combination of a handle, a jaw having forward and rearward faces and adapted to be turned end for end, a pin for attaching said jaw to said handle, said handle having lugs *o* and said jaw having recesses on its outer side faces in which said lugs lie in the fastened position, said jaw having circular faces *n* surrounding an edge of said lugs, and abutments between said jaw and handle preventing any turning of said jaw on said handle.

5. In a chain pipe wrench, the combination of a handle and a jaw having forward and rearward working faces on the same side of the jaw, said jaw having a solid or continuous gripping portion and bifurcated gripping portions at each end thereof, whereby said jaw is reversible on the handle, and said wrench is readily usable for pipe, fittings and flange turning work, the face of said solid portion and of each of said bifurcated portions being of substantially the same length.

6. A chain pipe wrench having a chain, a curved working face or jaw comprising a solid or continuous gripping portion and a bifurcated gripping portion, and lugs above said jaw for engaging said chain, said bifurcation admitting said chain therein and extending into said jaw substantially below the level of said lugs, and said solid and bifurcated portions rendering said wrench readily usable for pipe, fittings and flange-turning work on a substantial range of sizes.

7. A chain pipe wrench having a chain and a curved working face or jaw comprising a solid or continuous gripping portion and a bifurcated gripping portion, said bifurcation admitting said chain therein, and said solid and bifurcated portions rendering said wrench readily usable for pipe, fittings and flange-turning work on a substantial range of sizes of pipe, said jaw having a width approximately equal to the radius of curvature of said jaw.

8. A chain pipe wrench having a chain and a curved working face or jaw comprising a solid or continuous gripping portion

and a bifurcated gripping portion, said bifurcation admitting said chain therein, and said solid and bifurcated portions rendering said wrench readily usable for pipe, fittings and flange-turning work on a substantial range of sizes of pipe, said jaw having a radius of curvature having a representative length of two inches for a size of wrench applicable for a range of pipes from $\frac{3}{4}$ " to 10 2 to $2\frac{1}{2}$ inches in diameter.

9. A chain pipe wrench having a chain and a curved working face or jaw comprising a solid or continuous gripping portion and a bifurcated gripping portion, said bifurcation admitting said chain therein, and said solid and bifurcated portions rendering said wrench readily usable for pipe, fittings and flange-turning work on a substantial range of sizes of pipe, and a point of suspension of said chain opposite said jaw substantially at the center of curvature of said jaw.

10. A chain pipe wrench having a chain and a curved working face or jaw comprising a solid or continuous gripping portion and a bifurcated gripping portion, said bifurcation admitting said chain therein, and said solid and bifurcated portions rendering said wrench readily usable for pipe, fittings and flange-turning work on a substantial range of sizes of pipe, and a point of suspension of said chain at the rear of said jaw substantially on a tangent to the lowermost point of the curve of said jaw.

11. A chain pipe wrench having a chain and a curved working face or jaw comprising a solid or continuous gripping portion and a bifurcated gripping portion, said bifurcation admitting said chain therein, and said solid and bifurcated portions rendering said wrench readily usable for pipe, fittings and flange-turning work on a substantial range of sizes of pipe, and a point of suspension of said chain, opposite said jaw and at the rear of said jaw, said points being spaced apart a distance substantially equal or greater than the radius of curvature of said jaw.

12. A chain pipe wrench having a chain

and a curved working face or jaw comprising a solid or continuous gripping portion and a bifurcated gripping portion, said bifurcation admitting said chain therein, and said solid and bifurcated portions rendering said wrench readily usable for pipe, fittings and flange-turning work on a substantial range of sizes of pipe, and a point of suspension of said chain, opposite said jaw and at the rear of said jaw, said points being spaced apart a distance substantially equal or greater than the radius of curvature of said jaw, said point of suspension opposite said jaw being substantially at the center of curvature of said jaw.

13. A chain pipe wrench having a chain and a curved working face or jaw comprising a solid or continuous gripping portion and a bifurcated gripping portion, said bifurcation admitting said chain therein, and said solid and bifurcated portions rendering said wrench readily usable for pipe, fittings and flange-turning work on a substantial range of sizes of pipe, and a point of suspension of said chain, opposite said jaw and at the rear of said jaw, said points being spaced apart a distance substantially equal or greater than the radius of curvature of said jaw, said point of suspension opposite said jaw being substantially at the center of curvature of said jaw, and said point of suspension at the rear of said jaw being substantially on a tangent to the lowermost point of the curve of said jaw.

14. A chain pipe wrench having a chain and a curved working face or jaw comprising a solid or continuous gripping portion and a bifurcated gripping portion, said bifurcation admitting said chain therein, and said solid and bifurcated portions rendering said wrench readily usable for pipe, fittings and flange-turning work on a substantial range of sizes of pipe, the minimum length of said bifurcated portion substantially equaling the length of said solid portion.

In witness whereof, I have hereunto signed my name.

GEORGE W. BUFFORD.
